UNITED STATES PATENT OFFICE

2,017,336

CONCRETE SLAB

Earl C. Alexander, Glen Ellyn, Ill., assignor to
 Massey Concrete Products Corporation, Chi-
 cago, Ill., a corporation of Virginia

Application July 31, 1933, Serial No. 682,907

6 Claims. (Cl. 238—8)

The present invention relates to concrete slabs, and is particularly concerned with concrete slabs of the type adapted for use in constructing a roadway over railway grade crossings, and for other purposes.

The present concrete slab and railway crossing is an improvement over the structures disclosed in my prior Patent No. 1,832,803, issued November 17, 1931, on Crossing slabs, but the present 10 structures have certain features in common with the crossing slabs covered by that patent, which is exemplary of the prior art.

In the concrete railway crossings of this type of the prior art the crossing slabs have been of sufficient depth or thickness to correspond to the 15 depth of the rail, and when the slabs rest directly upon the ties the upper surface of the slabs is substantially flush with the top of the rails. When the ties and rails are originally installed they are, of course, properly located so far as it is possible and the slab finds bearing 20 surface upon a plurality of the ties across which the slab extends.

As time passes, however, the various ties settle 25 unequally, and a tie which may be supported by relatively soft terrain will settle more than one which happens to be located upon a more solid base.

One of the troubles encountered by installations 30 of the prior art is that the slabs may rock upon one of the higher ties, due to their lack of support at the lower ties which have settled. Every time a vehicle passes over one end of such a rocking slab, the slab is forcibly rocked back 35 and forth, or it may be subjected to unusual strains when both wheels of the vehicle encounter the slab, the higher supporting tie being located in between the wheels in the middle of the slab. As a result of the uneven settling of the road 40 bed, and ties, and the resultant rocking of the slabs, the slabs may be cracked or broken, and in some cases the rocking slab might project upward to catch something dragging from the train, and possibly cause a wreck or injury to the train. 45

The crossing slabs of the prior art are also more difficult to remove for track maintenance or other work, as it is necessary to start at one side of the railway crossing and take up all of 50 the slabs until the defective slab is reached in the installations of the prior art which employ dowels or pins for maintaining the slabs at the same level with respect to each other, and such slabs of the prior art are also provided with lifting devices which cannot be used for the removal 55

of a single slab from the middle or central part of a crossing.

One of the objects of the invention is the provision of an improved railway crossing assembly in which the concrete crossing slabs are so located and secured that there is no possibility of loosening or rocking of the slab due to unequal settling of the ties. 5

Another object of the invention is the provision of an improved concrete slab which is reversible 10 so that when one side of the slab wears excessively it may be turned over to use the other side.

Another object of the invention is the provision of an improved concrete slab for railway crossings or the like, which is provided with an im- 15 proved form of securing and/or lifting devices, by means of which the slabs are firmly secured in place in such manner that they are unaffected by the unequal settling of certain ties, and also so that any single slab may be released and lifted 20 out of its place for replacement, reversal, track maintenance, or any other purpose without disturbing the rest of the crossing.

Another object of the invention is the provision of an improved form of the metal armor for the 25 edges of the slab and an improved mode of assembling and installing the concrete slabs with the ties and rails at a grade crossing.

Other objects and advantages of the invention will be apparent from the following description 30 and from the accompanying drawings, in which similar characters of reference indicate similar parts throughout the several views.

Referring to the drawings, of which there are three sheets:

Fig. 1 is a top plan view of a railway crossing constructed according to the present invention and utilizing the improved form of slabs;

Fig. 2 is a vertical sectional view taken on the plane of the line 2, 2 of Fig. 1, looking in the direction of the arrows, showing the mode of support and securing for the concrete slabs;

Fig. 3 is another vertical sectional view taken transversely of the rails on the plane of the line 3, 3 of Fig. 1, looking in the direction of the arrows, showing the mode of assembly of the concrete slabs with the ties and rails and the spacing members;

Fig. 4 is an enlarged fragmentary detailed view of the concrete slabs, rails, spacers and securing 50 devices taken on the plane of the line 4, 4 of Fig. 1, looking in the direction of the arrows;

Fig. 5 is a modification taken on the plane of the line 5, 5 of Fig. 1, showing another type of securing device, which is also employed in Fig. 1; 55

Fig. 6 is a fragmentary vertical sectional view taken through a supporting tie and adjacent ends of slabs, showing another modified form of securing device which may also be employed in Fig. 1;

Fig. 7 is a detailed plan view of an improved concrete slab constructed according to the present invention;

Fig. 8 is a side elevational view of the concrete slab;

Fig. 9 is a vertical sectional view through the slab on the plane of the line 9, 9 of Fig. 7, looking in the direction of the arrows, showing the reinforcement and arrangement of the metal armor;

Fig. 10 is a top plan view of the blank or channelled member from which the metal armor is constructed; and

Fig. 11 is a top plan view of one of the corners of the armor, showing the mode of securing the overlying flanges of the armor together by welding.

Referring to Fig. 1, a railway grade crossing installation constructed according to the present invention preferably has its slabs running longitudinally of the rails. The slabs may be constructed of various appropriate sizes, and the present installation is merely exemplary of the preferred sizes which are readily adaptable to the standard sizes of ties and rails. The thickness of the slab will depend upon the weight and height of the rail, the heavier rails being higher. For example, with a 130 pound rail, six and one-half inches high, a slab four inches thick may be employed, or approximately so. Railway ties are conventionally eight feet six inches long, seven inches deep, and nine inches wide, and the ties are usually laid on eighteen inch centers.

It should be understood that the present slabs may be made of various sizes and may span different numbers of ties, if desired, or may be adapted to ties laid upon different centers or ties of different size. With a tie of conventional size and conventional installation mentioned, the slab may, for example, be four and one-half feet in length, in which case the slab would extend over three of the spaces between ties and over two intermediate ties, the slab being supported at its ends upon two ties.

In other cases the slab might be made six feet in length, extending over three intermediate ties and four of the eighteen inch spaces between the ties.

I prefer to cover the space in between the rails with pairs of slabs extending longitudinally, in which case the slabs 11 may be approximately twenty-five and one-eighth inches in width, while the slabs 12, 13, extending longitudinally of the rails and outside the rails, may be sixteen and three-quarters inches in width.

Referring to Figs. 7 to 11, these are views showing the various features of construction of an improved type of armored slab, but I desire it to be understood that the slabs disclosed in my prior patent mentioned may also be employed in the same way. The concrete slab 14 of Fig. 7 is provided with an exterior channelled frame 15 of steel, having a vertically extending web 16 and a pair of overlying flanges 17 and 18.

In order to form the metal armor a channelled member of appropriate length is taken, as shown in Fig. 10, and is provided with mitered ends 19, 20 and with intermediate mitered portions 21, 22, 23 cut out of the flanges 17, 18 at an angle of forty-five degrees to the length of the chan-

nel, the cut-out portions 21, 23 being located at the points of the corners of the frame. The channel 16 may then be bent at the points 24, 25, 26, bringing the adjacent edges 27 and 28 of the flanges 17, 18 of any cut-out portion together, as shown in Fig. 11. The parts of the flanges 17, 18 may then be welded together at 27, 28 on the top and at the bottom of the frame and at the ends 19 and 20 of the channel the flanges 17 and 18 respectively may be welded together and the ends of the web 16 may be welded together.

It is thus possible to provide a frame of the type shown in Fig. 7, having substantially continuous flanges 17 above and continuous overlying flanges 18 below these flanges or side webs of the channel being directed inwardly around the frame.

When the slabs disclosed in my prior patent or disclosed herein are made thinner than the height of the rails, a stronger mixture of concrete is preferably employed, and the reinforcement may also be made stronger so as to enable the slab to support any weight which it might encounter. Thus the slab may be provided with reinforcing 29, 30, consisting of networks of longitudinally and transversely extending equally spaced rods or bars, the rods or bars preferably being of such shape that they form an anchorage in the concrete, being secured together at their intersections. These rods or bars may be secured to the armor and frame 15 or they may be unsecured, being merely laid in the concrete as shown in Figs. 8 and 9.

The concrete is poured into the slab and finished on each side flush with the upper or outer surfaces of the flanges 17 and 18 so that the flanges 17 and 18 set in flush with the outer surfaces 31, 32 of the slab. Both sides or surfaces 31, 32 of the slab may be finished together so that the slab is reversible, and either side may be used.

It has been customary in the prior art to provide the slabs with apertures or bores extending into the edge of the slabs for the purpose of receiving dowels or metal pins which extend into the adjacent bores of two adjacent slabs and hold the slabs in substantially the same plane. These bores are also used for lifting devices, but this makes it necessary to remove certain slabs in order to gain access to the edges of the slab which is to be lifted.

The slabs constructed according to the present invention are preferably provided with metal spools 33 suitably located to receive securing bolts, spikes, or other devices. The spools 33 are preferably of the same length as the thickness of the slab, and they are provided with an intermediate cylindrical portion 34 having a longitudinally extending bore 35 of sufficient size to receive the bolt or other securing device. At each end of the cylindrical portion 34 the spool 33 is provided with a substantially cylindrical enlargement 36 having a counterbore 37 of sufficient size to receive the nut or head of the bolt and to permit a socket wrench to be inserted about the head or nut when the bolt is in place. The enlargements 36 at each end of the spool 33 also serve to anchor the spool in the slab as the concrete of the slab is held about the cylindrical portion 34 and engages shoulders 38, 39 of each of the enlargements 36.

Two of these metal spools are preferably utilized in each slab, the spools or armored bores being located approximately midway between the

edges of the slab at each end and sufficiently spaced from the end to clear the metal frame 15. If desired, however, the spools may be located at the four corners of the slab or a three point 5 mode of securement may be utilized.

Referring to Fig. 1, it will be observed that when the outside slabs and center slabs are made of the dimensions specified it is only necessary to utilize four rows of slabs extending longitudinally of the rails to construct a single track crossing. The slabs 10 to 13 are of suitable length so that they span the ties 40, 41 in Fig. 2, and may be supported only at their ends on the ties 42, 43. In order to support the slab 14 above the ties 40, 41, the ties 42, 43 are provided with spacing supporting members 44, 45.

20 The spacing supporting members 44, 45 consist of pieces of lumber which are preferably of the same width as the ties, in this case about
25 nine inches and of sufficient thickness to support the slab 14 flush with the tops of the rails 45, 46. Such a spacer would be approximately two and one-half inches thick in the case of a one hundred and thirty pound rail which is six and one-half inches high, provided a slab four inches thick were employed. The slab being six feet or four and one-half feet in length, either one of which figures is a multiple of eighteen inches, the center spacing of the ties, each slab would
30 come to approximately the middle of the supporting tie, leaving sufficient space for the support of the end of the adjacent slab. Both the slabs which are supported on the tie 42, for example, may be secured in place, and the spacer
35 44 may be secured in place by means of lag screws 47, 48 which pass through the spools 33 and through the spacing member 44, and have their threaded ends firmly embedded in the tie 42. The heads of the lag screws 47, 48 are, of course,
40 below the upper surface of the slab or crossing, since the counterbore 37 of each spool 33 is of sufficient size to receive entirely the head or nut of the bolt.

45 In some installations the outside slabs may be arranged with their edges immediately adjacent to the rails 45, 46, but it is preferable to use a longitudinally extending spacing member 49 of suitable shape to provide a flat upper surface 50 spanning the space between the slab and the top 50 of the rail 45, a suitable flat bottom surface 51 resting upon the supporting member 44, and a suitable flat outer surface 52 engaging the channelled frame of the outer slab.

The inner surface 53 of the spacer 49 may be shaped complementarily to the outside of the rail. The inner slabs are also preferably spaced from the rail by a relatively narrow grooved spacer 54 having flat surfaces upon both sides and adapted to engage the rail slab and supporting member 44, having a groove 55 at the top for receiving the flange of the car wheel.

The spacing members 49 and 54 may also be spiked to the supporting members 44 and ties 40 to 43. The spacing members 44 are preferably cut out at 56 and provided with a beveled portion 57 in which recesses 58 may be cut for receiving the heads of the spikes so that the spacing members 44 may lie flatly on the ties without interference from the supporting flanges or base of the rail or interference from the spikes 59. At each end of the crossing the slabs may be further protected by a substantially trapezoidal strip of lumber 60, having plane sides 61, 62 and 63 at right angles to each other, and having an upper bevelled surface 64 which provides an endwise

approach from the railway to the crossing.

Referring to Fig. 3, where the grade crossing is installed in a concrete road, the adjacent sections 65, 66 of the concrete road are also preferably finished with a channelled metal member having a web 67 and flange 68 which extends over the concrete 66 and protects the corner thereof.

Referring to Fig. 5, this is another modification, in which the metal spools 33 are suitably spaced from the end of the slab so as to be located with the bore 35 adjacent the vertical sides of the ties. In such case a modified form of securing device may be utilized, which comprises a bolt 69 having an upper threaded portion 70 for receiving a nut 71 which is received in the counterbore or socket 37.

The bolt 69 should be of suitable length so that the end of the bolt does not project above the slab and the bolt 69 is provided with a laterally 20 turned end 72 having an upwardly turned point 73 for engaging in the bottom of the tie 75 and preventing rotation of the bolt after the bolt has once engaged the tie. In such case the slabs may be removed by loosening the nut 71 and 25 turning the bolt 69 so that its end 72 rotates out from under the tie 75.

Referring to Fig. 6, this is a modified form of securing device in which the spools are again suitably located to receive bolts at each side of the tie. The bolts 76, 77 pass through the horizontal flange 78 of an angle iron 79 which engages the bottom of the tie. The angle iron 79 is drawn into engagement with the tie 80 by the two bolts 76, 77, which in turn pass through the spools 33 of two adjacent slabs.

In this case also the bolts should be of such length that they do not project above the slabs. The slabs may be removed by wholly removing the nuts 81 of the bolts 16, 77. It will thus be observed that I have invented a new concrete slab railway crossing in which the slab may be supported only at its ends out of engagement with the intervening ties. It is practically impossible for such a slab to rock on the ties which support it, since it is supported only at its ends. In case the supporting ties settle unduly, the only effect would be a slight settling of the ends of the slabs, but it is unlikely that even such settling could occur with respect to the slabs because the spacing members 44 engage the tops of the base flanges of the rails and prevent the supporting members 44 from settling away from the rails. Thus the slabs should always be supported with their tops substantially flush with the tops of the rails.

The spools, armor and other features of the slab being the same at both sides or ends, each of the slabs is reversible and when excessive wear appears on one side the slab may be turned over and used again for a long period of time. The metal armor protects all parts of the edge of the slab and provides a substantially integral covering for the edge and over-hanging the upper surfaces of the slab prevents any cracking or wear of the slab at these points. The slabs firmly secured in place according to the present installation, there is less likelihood of theft of an individual slab than when the slabs are merely laid in place and the location of the securing spools extending to the upper surfaces of the slab enables them also to be used for lifting devices through the insertion of a bolt or hook or bent rod adapted to bind in the bore of the spool. Any separate slab may be removed without disturbing any of

the other slabs, and the maintenance and repair of the road bed is thus facilitated.

While I have illustrated a preferred embodiment of my invention, many modifications may be made without departing from the spirit of the invention, and I do not wish to be limited to the precise details of construction set forth, but desire to avail myself of all changes within the scope of the appended claims.

10 Having thus described my invention, what I claim is new and desire to secure by Letters Patent of the United States, is:

15 1. A railway crossing assembly comprising a plurality of ties and rails and a plurality of longitudinally extending concrete slabs, said slabs being of sufficient width to fill the space between the rails and cover the ties outside of the rails, each of said slabs extending longitudinally of the rails over a plurality of ties, said slabs being supported solely at their ends, and means passing through said slabs and secured to said ties for preventing relative movement between said slabs and ties.

20 2. A railway crossing assembly comprising a plurality of ties and rails and a plurality of longitudinally extending concrete slabs, said slabs being of sufficient width to fill the space between the rails and cover the ties outside of the rails, each of said slabs extending longitudinally of the rails over a plurality of ties, said slabs being supported solely at their ends, and means passing through said slabs and secured in said ties for preventing relative movement between said slabs and ties, said means comprising metallic spools 35 embedded in the concrete of said slabs, and threaded members secured in said spools and having offset ends engaging below predetermined ties.

30 3. A railway crossing assembly comprising a plurality of ties and rails and a plurality of longitudinally extending concrete slabs, said slabs being of sufficient width to fill the space between the rails and cover the ties outside of the rails, each of said slabs extending longitudinally of the rails over a plurality of ties, said slabs being supported solely at their ends, and means passing through said slabs and secured in said ties for preventing relative movement between said slabs and ties, said means comprising metallic spools embedded 45 in the concrete of said slabs and pairs of bolts

passing through the spools of adjacent slabs and having their lower ends secured to metal members located below the supporting ties.

4. In a railway crossing installation, the combination of a plurality of ties with a pair of rails supported by said ties, a concrete crossing slab of sufficient length to span the space between a plurality of ties, the length of said slab being adapted so that the slab terminates substantially midway between the sides of predetermined ties, spacing 10 members carried by the ties located beneath the ends of said slab, and means carried by said slab, securing said spacing means and said slab to the ties located under the ends of said slab whereby the slab is supported solely at its ends and is 15 spaced from intermediate ties underneath the slab.

5. In a railway crossing installation, the combination of a plurality of transversely extending ties with a pair of rails supported by said ties, a 20 concrete crossing slab of sufficient length to span the space between a plurality of ties, said slab comprising a metal frame having over-hanging inwardly extending flanges and a filling of concrete between said flanges, the length of said slab 25 being such that the slab terminates substantially midway between the sides of predetermined ties, spacing members carried by said predetermined ties and located beneath the ends of said slab and above said ties, and securing means passing 30 through said slab and through said spacing means and extending into said predetermined ties whereby the slab is supported wholly at its ends and is spaced from the intermediate ties beneath the slab so as to prevent rocking of the slab on 35 said intermediate ties.

6. A railway crossing assembly comprising a plurality of ties and rails and a plurality of longitudinally extending concrete slabs, said slabs being of sufficient width to fill the space between the 40 rails and cover the ties outside of the rails, each of said slabs extending longitudinally of the rails over a plurality of ties, said slabs being supported solely at their ends, and means passing through said slabs and secured to said ties for preventing 45 relative movement between said slabs and ties, said means comprising threaded members having laterally projecting portions for engaging a tie whereby the slabs may be clamped to the ties.

EARL C. ALEXANDER. 50
